DESIGN FOR AN ARMREST FOR VEHICLE SEATS

Herbert Schmiege, Saginaw, Mich.

Application December 1, 1947, Serial No. 142,903

Term of patent 14 years

(Cl. D14—6)

To all whom it may concern:

Be it known that I, Herbert Schmiege, a citizen of the United States, residing at Saginaw, in the county of Saginaw and State of Michigan, have invented a new, original, and ornamental Design for Arm Rest for Vehicle Seats, of which the following is a specification, reference being had to the accompanying drawing, forming part thereof.

In the drawing:

Fig. 1 is a side perspective view of an arm rest showing my new design as it appears when seen in extended position;

Fig. 2 is a perspective view of the same, folded and seen from the side; and

Fig. 3 is a top view, extended as shown in Fig. 1.
I claim:

The ornamental design for an arm rest for vehicle seats, as shown.

HERBERT SCHMIEGE.
